VANITY CASE

Simon Morrison, New York, N. Y.

Application January 20, 1938, Serial No. 185,792

11 Claims. (Cl. 132—83)

This invention relates to vanity cases, which are carried by ladies for make-up purposes.

Included in vanity cases are a mirror, a powder puff, a supply of powder, and sometimes other articles. The "powder" may be in the form of an easily pulverizable cake, or it may be in loose form. Loose powder is preferable because of certain undesirable effects produced by the binder which is present in a cake of "powder". However, it is inherently difficult to carry loose powder about and use it in small quantities without untidy results. Thus, much effort has been devoted to the development of satisfactory forms of loose powder vanity cases.

Considerable success has been achieved in the efforts to satisfactorily enclose a supply of loose powder and render small quantities of it readily available for individual applications. However, rigid box-type vanity cases have been required for the purpose. These are in wide use, but they tend to be bulky and heavy, and they cannot be stowed and carried in some ladies' pocketbooks and handbags with the convenience of a flexible vanity case.

The general object of the present invention is to provide a flexible vanity case which will satisfactorily carry a supply of loose powder and render small quantities of the powder readily available for individual applications.

Another object of the invention is to provide for the replenishment of the powder supply in such a vanity case.

A further object of the invention is to provide a light weight, flexible vanity case which can be inexpensively manufactured on a quantity production basis.

Various other and specific objects of the invention will be apparent from the following disclosure of illustrative forms of the invention.

Figure 1 of the drawings is a plan view, showing a vanity case of the present invention in closed condition.

Fig. 2 is an elevation of the closed vanity case of Fig. 1, viewed in the direction of the arrow in Fig. 1.

Fig. 3 is a plan view, showing the vanity of Figs. 1 and 2 in open condition.

Fig. 4 is an enlarged cross section, taken in general on the line 4—4 of Fig. 3.

Fig. 5 is an enlarged detail section, taken in general on the line 5—5 of Fig. 4.

Fig. 6 is a plan of a modified vanity case in open condition.

Fig. 7 is a fragmentary plan view of a second

modification, the vanity case being in open condition.

Fig. 8 is a fragmentary plan view, showing a slightly different form of the powder magazine structure shown in Fig. 7.

Reference will first be had to Figures 1 to 5. The exterior of the case is formed of a strip of flexible sheet material, operatively subdivided into a center section 10 and flaps 11 and 12. Over the interior of center section 10 is a pocket-forming flexible sheet 14, which is secured to section 10 along edges A, B, and C. Adhesively or otherwise attached to flap 12 is a mirror 15. When the case is closed, flap 11 is folded over pocket-forming sheet 14 and then flap 12 is folded over flap 11 (see Fig. 2). Projecting from the outside of center section 10 is a strap 16 which is used to secure the case in closed condition, the free end of the strap being provided with a snap-fastener element 17 which cooperates with a second fastener element 18 mounted on the outside of flap 12.

Any suitable sheet material (e. g., leather) may be used for the outside case (sections 10, 11, and 12) and for pocket-forming sheet 14. Often the sheet material will be a laminated fabric, made up of a body layer having silk fabric of different colors secured to the two faces of the body layer. The cut edges of the material may be overseamed as shown in the drawings, e. g., at A, B, and C; and the overseaming may be used to secure sheet 14 to center section 10 along edges A and C.

Attached to sheet 14 is a rigid powder magazine assembly designated as a whole by 20. The main part entering into this assembly is a sheet metal stamping which includes a bottom portion 21, an annular wall portion 22, an annular rabbet portion 24, an annular rim 25, and eight attachment fingers 26. The bottom 21 is slotted to receive a corrugated roller 27 which is mounted on a shaft 28 that is inserted through holes in the wall 22 as shown in Fig. 4.

Pivotedly attached to the aforesaid sheet metal stamping is a sheet metal closure 30 having an annular bead 31, a thumb-nail portion 32, and latching flanges 33, 33 which project substantially perpendicularly from closure 30. When the closure 30 is in closed position, fingers 33, 33 project through holes 34, 34 in the main stamping and make snap engagement with the edges of the holes. In closed position the edge portion of closure 30 lies in rabbet 22, thus making a fairly powder-tight engagement. Preferably a definite powder seal is made by an annular felt gasket 35.

which is adhesively secured to bottom 21 and is engaged by bead 31 of cover 30. It will be seen that the powder magazine assembly includes a powder compartment closed by lid 30 which can be opened by inserting a thumb nail under portion 32.

The powder magazine assembly is positioned on top of sheet 14 and secured thereto by fingers 26 which pass through the sheet and are clinched 10 on the under side. Sheet 14 is provided with a slot at s through which the periphery of roller 27 projects into the puff compartment 36 that is formed between sheet 14 and the outer case structure. When a puff 37 is inserted into or 15 withdrawn from the puff compartment 36, the puff engages roller 27 and rotates the same, thereby feeding powder from the powder compartment to the puff.

In Fig. 6 the exterior case is the same as in Figs. 1 to 5 except that flap 11a extends at right angles to flap 15 and the puff compartment has its open edge at the side, as indicated by the position of puff 37. The powder magazine assembly is the same as in Figs. 1 to 5 except that 25 roller 27 is omitted and powder is allowed to sift through perforations p in bottom 21a. Of course, sheet 14a, to which the powder magazine assembly is attached, is cut away in an area corresponding to bottom 21a.

30 In Fig. 7 the bottom 21a of the powder compartment is perforated as in Fig. 6 and a slidable grid 40 is positioned against the bottom. This grid has a center portion provided with perforations p' which may be brought into register with 35 certain of the perforations p in bottom 21a. Additionally grid 40 has a series of bars 41 which cover and uncover perforations p in bottom 21a. Fingers 42, 42 project from the wall of the powder compartment and overlie grid 40. Integral with 40 grid 40 is an actuator extension 43 which passes through the wall of the powder compartment and up through a notch in rim 25a. By shifting extension 43 the grid 40 is moved to sift powder to puff 37, the action being similar to that of a kitchen flour sifter. Or, the opening and closing of the vanity case may be relied upon to sift the powder to the puff, while grid 40 is positioned to give the desired effective sifting opening.

50 Fig. 8 illustrates a variation of grid arrangement, in which the grid is shiftable by an extension 43a which projects in the direction of grid movement.

In compliance with the patent statutes, I have disclosed the best forms in which I have 55 contemplated applying my invention, but it will be understood that the disclosure is illustrative and not limiting.

What is claimed is:

1. A vanity case comprising: an exterior case 60 structure of flexible material; a rigid powder

magazine assembly within the exterior case, the magazine assembly having a compartment for loose powder; and means flexibly attaching the magazine assembly to the exterior case, there being a puff compartment between the magazine 5 assembly and the exterior case.

2. A vanity case as in claim 1, with means to effect the transfer of powder from the powder compartment to the puff compartment.

3. A vanity case as in claim 1, with means to 10 effect the transfer of powder from the powder compartment to the puff compartment, said means being actuated by a puff inserted and removed from the puff compartment.

4. A vanity case as in claim 1, in which the 15 exterior case includes a flap folded over the powder magazine assembly.

5. A vanity case as in claim 1, in which the exterior case includes two flaps, one folded over the powder magazine assembly, and the other 20 provided with a mirror and folded over the first flap.

6. A vanity case as in claim 1, in which the 25 bottom of the powder compartment is provided with a plurality of perforations.

7. A vanity case as in claim 1, in which the bottom of the powder compartment is provided with a plurality of perforations, and a slidable 30 grid is positioned adjacent to the bottom of the powder compartment.

8. A vanity case comprising: a case structure 35 of flexible material; and a metal powder magazine assembly attached to the flexible material, the magazine assembly having a compartment for loose powder, and having a hinged closure for the powder compartment.

9. In a vanity case, a powder magazine assembly comprising: a sheet metal powder compartment formed with an annular metal rim; an annular gasket positioned within the powder 40 compartment; and a sheet metal closure for the powder compartment, the closure being movable to closed position within the rim and having an annular bead to engage said gasket.

10. In a vanity case, a powder magazine 45 assembly comprising: a sheet metal powder compartment formed with an annular metal rim and an annular rabbet within the rim, the rabbet portion being provided with at least one latch hole; and a hinged sheet metal closure movable 50 into the rabbet, the closure having a latching finger which projects through the latch hole and makes snap-engagement with an edge of the hole.

11. A structure as in claim 10, in which there 55 is an annular sealing gasket, and the closure is provided with an annular bead which engages the gasket when the closure is in closed position.

SIMON MORRISON. 60
